UNITED STATES PATENT OFFICE.

ROBERT EMMET KEOUGH, OF MONTREAL, QUEBEC, CANADA, ASSIGNOR TO THE AMERICAN FORK & HOE COMPANY, OF CLEVELAND, OHIO, A CORPORATION OF OHIO.

RAIL JOINT.

Original application filed April 3, 1926, Serial No. 99,475. Divided and this application filed December 17, 1928. Serial No. 326,507.

My invention relates to rail joints and has a special application to the problem of prolonging the term of usefulness of the rail joint elements commonly employed for the purpose of joining railroad rails in end to end relation.

It has been found necessary to remove the laterally disposed clamping side bars of rail joints after a certain period of effective use, due to the fact that the movement of trains over the rails employing such joint causes the side bar elements to wear away at the portions of their surfaces wherein contact is had with the rail flanges. These side bar elements are usually made of a good quality of steel, and their replacement is expensive in material and labor required.

In rail joints employed for the purpose of securing the abutting ends of railroad rails together, it is the general practice to employ a pair of rail joint side bars, one on either side of the joined rails, compressing these together by means of bolts passing through aligned openings in the side bars and the rail, and in such cases it is usual to employ side bars having inclined upper and lower rail engaging faces for engagement with the under side of the rail head and the upper side of the rail flange, respectively.

It has been found that in use, considerable wear of the rail joint side bar elements and of the contacted portions of the rail head and rail flange occurs, due to pounding of the joined rail ends by the passage of the supporting wheels of heavy railroad trains. It has been found, moreover, that this wear occurs in greater measure as the abutting ends of the rails are approached, and that the wear is progressively less and less in contacting portions of the rail joint side bars and the rail from the abutting ends of the rails along the rails.

Sometimes where one-way railway tracks are employed, the fishing surfaces of the "receiving" rail flange and of the joint bar adjacent thereto are worn to a much greater extent than the similar surfaces relating to the "leaving" rail.

The practice generally has been to discard the side bars when the wear above mentioned becomes excessive and the rail cannot be securely held by the side bars, even when the securing bolts are tightened by turning

the nuts provided upon their ends, such side bars have generally had to be replaced. If any effort has been made to employ shims to take up the wear between the bars and rail, such effort, so far as I am aware, has not prior to my invention attained any considerable degree of success. I find that by employing a shim shown herein in varying forms tapered in transverse sections from the portions of greatest thickness, at the middle of the shim, to its ends, whereat the shim is much thinner than at the middle, I am enabled to take up the wear substantially commensurable with the amount of the wear of the portions of side bars and rails contacting with the shim. In such constructions, I place the thicker middle portion of the shim at that portion of the joint adjacent the abutting ends of the railroad rails, where the most wear occurs.

Such a shim is described and broadly claimed in my copending application Serial No. 99,475, filed April 3, 1926, of which the present application is a division.

My present invention is directed more particularly toward the provision of a wear compensating shim for rail joints of railways employed largely for "one-way" traffic, or under such other conditions wherein there results a crevice of greater size under the rail head of one rail of a pair of abutting rails than under the other rail head.

In my co-pending application Serial No. 232,539, filed November 11, 1927, I disclosed and claimed separate wear compensating elements adaptable for use under such conditions. The present application is directed to the provision of a one-piece shim adaptable for insertion between the adjoining rail ends and the joint side bar to compensate for the different amounts of wear occasioned by movement of the different rail ends.

An object of my invention, therefore, is to increase the effective life of the side bars employed for the purpose of securely joining longitudinally aligned rails together.

Another object of my invention is to permit the employment of side bar elements having wearing surfaces of inexpensive material, and which, except for my invention, would be worn away even more rapidly than are the like surfaces of the rail joint side bar elements now commonly in use, but which,

because of exposure to wear, are now required to be made of a superior wear-resistant material.

Another object of my invention is to effect 5 the production of an element which may be used as a shim or liner, as an article of manufacture, and which may be added to a worn rail joint to effect its continued use in a highly efficient and satisfactory manner.

10 Another object of my invention is to provide a one-piece wear compensating shim for rail joints adaptable to differently compensate for different amounts of wear occasioned by "pounding" by the ends of two abutting 15 rails of a rail joint.

Another object of my invention is to provide a one-piece wear compensating shim for rail joints adaptable to differently compensate for different amounts of wear occasioned by "pounding" by the ends of two abutting rails of a rail joint, wherein one 20 of the rails is traversed by the traffic passing over the rails generally before the other rail.

25 Other objects of my invention and the invention itself will be readily apparent from the accompanying description, in which description reference will be had to the drawings accompanying this specification and 30 forming a portion thereof.

Referring to the drawings:

Fig. 1 illustrates in perspective a wear compensating means for rail joints embodying the principles of my invention.

35 Fig. 2 is a similar view of a rail joint employing the wear compensating means of Fig. 1.

Fig. 3 is a section taken transversely of the joint between the rail ends of Fig. 2.

40 Fig. 4 is a perspective view of a wear compensating means which is another embodiment of my invention.

Fig. 5 is a side elevational view of a rail joint employing the wear compensating means of Fig. 4, the rail joint side bar being removed in this figure to permit a view 45 of the shim as if in place in the joint.

Referring now first particularly to Figs. 1 to 3 inclusive, illustrating an embodiment 50 of my invention, the said embodiment comprises a shim in the form of an elongated strip of tempered steel, which is bent longitudinally to provide a pair of angularly disposed portions, namely a shim portion 1 and an apron portion 2.

Both of these portions 1 and 2 taper in thickness in both directions from the middle of the shim, longitudinally thereof, one longitudinally disposed tapered end portion 60 3 being in all portions thicker than the corresponding portions of the other longitudinally disposed shim portion 4.

Contiguous to the junction 5 of the two 65 shim ends, both shim portions 3 and 4 are of greatest thickness, the thickness of

the strip decreasing progressively therefrom toward the ends 6 and 7 respectively for the portions 3 and 4.

Although I have illustrated the shim of Fig. 1 as having a thicker portion 3 so disposed as to fit under the head of the rail 8, and the thinner portion 4 to fit under the head of the rail 9, where the rail 8 occasions greater wear than the rail 9, it will be understood that I contemplate placing a shim 70 otherwise formed like that illustrated in Fig. 1, but with the relative positions of thicker and thinner portions reversed from that shown in Fig. 1, "rights" and "lefts" being thereby provided for rail joints. As 75 an alternative expedient to provide "rights" and "lefts", a shim such as illustrated in Fig. 1 may be inverted so that the apron portion 2 is placed between the upper surface of the rail joint side bar, such as 10, 80 and the under surface of the head of the rail 8, and in such case what I have before termed wear compensating or shim portion 1, will depend between the web 11 of the rail and the inner surface of the joint side bar 10. 85

I prefer, however, to employ the shims in "rights" and "lefts" as above referred to and I further prefer to provide the apron portion such as is illustrated at 22, Fig. 4, with one or more depending apron prongs 90 12 and 13 having their outer lateral edges 14 preferably so spaced as to be engageable with rail joint bolts 15 to prevent longitudinal displacement of the shim in the joint while in use, as illustrated in Fig. 5. 95

While in the shim of Fig. 1 I have illustrated the tapering from the middle portion 5 toward the ends, as accomplished by similarly converging inner and outer surfaces of the strip, I may sometimes employ a shim 105 having either the outer or the inner surfaces longitudinally straight and with the other inner or outer surface converging from the thickened middle portion of the shim toward the longitudinal ends. 100

Such an arrangement is illustrated specifically in connection with the disclosure of Fig. 4, though either this or the arrangement of Fig. 1, in this respect, may be applicable to shims irrespective of whether or not the depending prongs 12 and 13 are employed. 110

The shims as above described, have a particular application in connection with rail joints, on "one-way" railroad tracks. Under conditions of predominately one-way traffic, the "receiving" rail occasions a great deal more wear in the rail joint than the "leaving" rail, and therefore the thickened end of the shims of my present invention would be inserted in the grooves thus occasioned by the receiving rail, and the thin edge of the shim inserted in the grooves occasioned by the lesser wear of the leaving rail. 120

Having thus described my invention in cer- 130

tain embodiments I am aware that numerous and extensive departures may be made from the embodiment herein illustrated and described but without departing from the 5 spirit of my invention.

I claim:

1. A metallic rail joint shim of integral construction adapted to be placed between worn portions of a rail joint side bar and a 10 pair of substantially abutting rails, of metallic material, tapered toward the ends and having two joined longitudinally extending portions of different thicknesses.

2. A metallic rail joint shim adapted to 15 be placed in a crevice created by wear of contacting portions of a rail joint side bar with a pair of longitudinally aligned railroad rails, one of said rails being a "leaving" rail and the other being a "receiving" rail, of 20 a track used mostly for one-way traffic, the portion thereof adapted to be fitted between the side bar and the "receiving" rail being of greater thickness than the portion thereof adapted to be fitted between the side bar 25 and the "leaving" rail.

3. A metallic shim for rail joints adapted to be placed between a rail joint side bar and each of a pair of substantially abutting rails, having an end portion insertable between 30 worn parts of one of the rails and the side bar, of greater thickness than its other portion, both portions of the shim being tapered toward the ends of the shim.

4. A metallic rail joint shim adapted to be 35 placed in a crevice created by wear of contacting portions of a rail joint side bar with a pair of longitudinally aligned railroad rails, one of said rails being a "leaving" rail and the other being a "receiving" rail, of a 40 track used mostly for one-way traffic, the portion thereof adapted to be fitted between the side bar and the "receiving" rail being of greater thickness than the portion thereof adapted to be fitted between the side bar and 45 the "leaving" rail, at least one of said portions being tapered in thickness toward its free end.

5. A metallic rail joint shim of integral construction adapted to be placed between

worn portions of a rail joint side bar and a 50 pair of substantially abutting rails, of metallic material, tapered toward the ends and having two joined longitudinally extending portions of different thicknesses, said shim being of angular cross sectional form 55 throughout its length and comprising a depending apron portion adapted to project downwardly between the web of the rails and the joint bars.

6. A metallic rail joint shim of integral 60 construction adapted to be placed between worn portions of a rail joint side bar and a pair of substantially abutting rails, of metallic material, tapered toward the ends and having two joined longitudinally extending 65 portions of different thicknesses, said shims being of angular cross sectional form throughout its length and comprising a depending apron portion adapted to project downwardly between the web of the rails 70 and the joint bars, said apron comprising a downward extension adapted to contact laterally with the bolts securing the bars to the rails to prevent longitudinal displacement 75 of the shim in the joint.

7. A metallic rail joint shim of integral construction adapted to be placed between worn portions of a rail joint side bar and a pair of substantially abutting rails, of metallic material, tapered toward the ends and having two joined longitudinally extending portions of different thicknesses, said shim being of angular cross sectional form throughout its length and comprising a depending apron portion adapted to project 85 downwardly between the web of the rails and the joint bars, said apron comprising a downward extension adapted to contact laterally with the bolts securing the bars to the rails to prevent longitudinal displacement 90 of the shim in the joint, said downward extension comprising two separate extension aprons, each engageable with a separate joint bolt.

In testimony whereof I hereunto affix my 95 signature this 30th day of Nov., 1928.

ROBERT EMMET KEOUGH.
